UNITED STATES PATENT OFFICE.

ANTHONY CHIARELLI, OF NEW YORK, N. Y.

MOTION-PICTURE-PROJECTING MECHANISM.

1,342,040.

Specification of Letters Patent.

Patented June 1, 1920.

Application filed November 20, 1918. Serial No. 263,332.

To all whom it may concern:

Be it known that I, ANTHONY CHIARELLI, a citizen of the United States, residing at New York, in the county and State of New 5 York, have invented certain new and useful Improvements in Motion-Picture-Projecting Mechanism, of which the following is a specification.

This invention relates generally to motion 10 picture projecting mechanism having more particular reference to the projection of the film against ignition from the heat of the lamp while being fed.

The invention has for an object to provide 15 an improved means whereby ignition of the films may be prevented.

A further object is to provide a mechanical means whereby the light rays from the lamp may be obstructed in the event of 20 breaking of the film.

Another object is to provide means whereby by the light may be cut off from the film in the event of the feed of the latter slowing down too much.

25 A further object is to provide a device of this kind in the form of an attachment capable of application to different machines.

For further comprehension of the invention, and of the objects and advantages 30 thereof, reference will be had to the following description and accompanying drawings, and to the appended claims in which the various novel features of the invention are more particularly set forth.

35 Figure 1 of the drawings is a plan view of the device applied to a motion picture projector.

Fig. 2 is a longitudinal vertical section on the line 2—2 of Fig. 1.

40 Fig. 3 is a transverse vertical section on the line 3—3 of Fig. 1.

Fig. 4 is a fragmentary elevation showing the shutter and its supporting means.

Fig. 5 is an enlarged detail vertical section through one of the control devices.

Fig. 6 is a horizontal section on the line 6—6 of Fig. 5.

Fig. 7 is a detail transverse section taken on the line 7—7 of Fig. 1 and illustrating 50 particularly the connection of the attachment to the machine base to permit of lateral adjustment.

Fig. 8 is a detail view of one of the friction drive connections between the film 55 driven sprocket wheels and the governor.

In the drawings 1 indicates the main frame

of a motion picture machine, and 2, 3, 4 the toothed sprockets by which the film is advanced, these sprockets being rotated by usual mechanism. It is not considered necessary to illustrate such mechanism or the details of the machine since these are well known to those skilled in the art and illustration thereof is not essential to a proper understanding of this invention. A portion 60 of the usual lamp structure is shown at 5, while the film is indicated in position in Fig. 2 by the heavy line 6.

According to my invention I provide a device, or a pair of devices, in position to be 70 engaged by the film and rotated thereby as it is advanced, the operation of these devices controlling the light obscuring device. In the present instance a pair of shafts 10 and 11 are suitably journaled on axes parallel 75 to the face of the film, respectively adjacent the top and bottom of the frame 1, and having rigidly fixed thereon sprocket wheels 12 and 13 which press against the film and the teeth 14 of which engage the usual perforations not shown, with which the side edges 80 of these films are provided, the sprocket wheels being thus caused to rotate as the film advances.

The light obscuring device is in the form 85 of a shutter 18 on the long end of a lever arm 19 pivoted as at 20 on the vertically adjustable upper end 21' of a post 21 formed integrally with an adjustable foot 22 having a telescopic connection with a base 90 23 which latter is mounted for transverse adjustment on a bracket 74 secured as by the bolts 75 to the base of the frame 1. The upper post section 21' may be connected to the lower section by means of bolts 21^a passing through suitable vertical slots in the overlapping portions of the two sections and having nuts 21^b threaded on their ends. A sheet of asbestos may be attached to the shutter to increase heat resisting qualities. 100

Secured at its lower end to the base 23 near the frame 1 is a skeleton standard 30 in the upper and lower ends of which are journaled shafts 31 and 32 co-axial with the shafts 10 and 11. These shafts 10 and 11 105 may be journaled in bearings 33 and 34, fixed to the frame 1, and extensions 35 and 36 of the standard 30.

The shafts 31 and 32 are driven from the shafts 10 and 11 by means of slip clutches 110 here in the form of disks 37 slidable on the latter shafts and provided with friction

faces 38 which are pressed yieldingly into engagement with friction faces 39 on disks 40, fixed to the shafts 31 and 32, by means of springs 41 bearing between the disks 37 5 and collars 42 adjustably secured to the shafts 10 and 11. A spline connection 43, Fig. 8, is formed between each of the disks 37 and each of the shafts 10 and 11.

Motion is imparted from the shafts 31 10 and 32 to a vertical shaft, here shown as composed of an upper section 45 and a lower section 46, by means of bevel gears 47 and 48 on the shafts 31 and 32 engaging with bevel gears 49 and 50 on the upper and 15 lower ends of the vertical shaft sections 45 and 46.

Mounted upon the shaft section 46 is a centrifugal governor device 51 whose sliding collar 52 carries a loose ring 53 to which 20 is attached one end of a cord 54, or other flexible connection, leading to the arm 19 of the shutter 18. As here shown this cord 54 leads over suitable pulleys 55 and has located therein a differential device in the 25 form of a bell crank having a short arm 56 and a long arm 57, the latter being adjustable in length by means of the telescoping section 57'.

Secured upon the lower shaft section 46 is 30 a centrifugal governor device 60 whose sliding collar 61 has a clutch surface 62 which engages a similar surface 63 on a collar 64 fixed to the lower end of the shaft section 45, the purpose of this being to "cut out" the 35 shaft section 45 from the lower shaft 11 when the feeding speed of the film falls too low.

The telescoping connection between the foot 22 and base 23 I have here shown as 40 formed by providing the foot with a slot 70 through which pass bolts 71 threaded into the base 23, the foot 22 and base 23 being of channel shape in cross section and the foot sliding within the base.

45 I provide for lateral adjustment of the device with respect to the machine by mounting the base 23 on a bracket 74 secured by bolts 75 to the base of the main frame 1, this bracket 74 having transverse slots 76 to receive bolts 77 passing through suitable 50 openings in the base 23. The bevel gears 47 and 48 are also shown secured to the shafts 31 by set screws 79 to permit of this adjustment, while the shutter arm 19 is made 55 in two parts connected by a slot and bolt connection 19'.

In addition to the differential bell crank for regulating the throw of the shutter with the governor, I have connected the cord 54 60 to the head of a screw 80 threaded into the arm 19.

As shown in Fig. 4, a pair of electrical contact members 90 and 91 may be mounted 65 respectively on the shutter arm 19 and standard 21, and adapted to make contact

when the shutter falls across the lamp house opening, these contacts being wired to a bell or other device, or to a solenoid whose armature is in the main circuit so as to shut off power and light when the governors stop functioning. 70

In operation the film engages the sprocket wheels 12 and 13 in its passage through the machine while the friction disks 37 and 40 have their frictional engagement adjusted 75 so as to require the combined pressure of the two pairs to drive the governor mechanism 51. Rotation of the shaft 45, 46, lifts the collar 52 and raises the shutter 18, through cord 54, away from its normal resting position in front of the lamp house opening. 80

The governor collar 61 is also lifted causing the clutch faces 62 and 63 to engage.

In the event of breakage of the film the 85 sprockets 12 and 13 will cease rotating and the collar 52 will fall, allowing the shutter to drop across the lamp house opening.

Should the speed of the film decrease below a desired point the governor 60 will 90 no longer keep the clutch faces 62 and 63 in engagement and, as the friction drive from the one pair of disks 37, 40 is insufficient to drive the device, the shaft section 45 will stop rotating and the shutter fall. 95

It will be apparent that the upper film engaging device could be eliminated, the advantage of the double arrangement being that a more instantaneous action is had when the film breaks at the entering point to the 100 machine.

Having thus described my invention, what I claim as new and desire to secure by Letters Patent is:—

1. In a motion picture projection machine, 105 the combination with film advancing means, of a device adapted to cut off the light rays to the film, a pair of independent elements operated by the film, and means whereby said elements act in coöperation with each other to control the functioning of the said device.

2. In a motion picture projection machine, 115 the combination with film advancing means, of a device adapted to cut off the light rays to the film, a pair of independent elements operated by the film, and means whereby said elements jointly control the functioning of the said device said means including a friction clutch for each of said elements. 120

3. In a motion picture projection machine, 125 the combination with film advancing means, of a device adapted to cut off the light rays to the film, a pair of independent elements adapted to be rotated by the film, a sectional shaft, means for providing a frictional drive engagement between said elements and the respective sections of the shaft, means including a centrifugal governor for operatively connecting the shaft sections to- 130

gether, and means including a centrifugal governor for connecting said shaft to said device to retain the latter in inoperative position.

5. 4. In a motion picture projection machine, the combination with a source of light and film advancing means, of means for cutting off the light from the film when the speed of the latter drops below a certain point, said means including a pair of rotatable members, and a centrifugal governor adapted to retain said members in operative engagement with one another.

5. 5. In a motion picture projection machine, the combination with film advancing means and a source of light, of a shutter hinged adjacent the source of light and adapted to cut off the light rays to the film, a device adjacent the film advancing means adapted to control the position of said shutter, a frame on which said device and said shutter are mounted, said frame comprising a pair of telescoping sections whereby said shutter may be adjusted toward or away from the said device.

25. 6. In a motion picture projection machine, the combination with film advancing means and a source of light, of a shutter hinged adjacent the source of light and adapted to cut off the light rays to the film, a device adjacent the film advancing means adapted to control the position of said shutter, a frame on which said device and said shutter are mounted, said frame comprising a pair of telescoping sections whereby said shutter may be adjusted toward or away from the said device, and means for vertically adjusting the hinge point of said shutter.

7. In a motion picture projection machine, the combination with a source of light and film advancing means, of a pair of wheels in engagement with the film, a light obscuring device, means for holding said device in inoperative position, and a frictional con-

nnection between each of said wheels and the said means, for the purpose set forth. 45

8. In a motion picture projection machine, in combination, film advancing means, a member adapted to be rotated by engagement with the film, a pair of electrical contact devices one of which is normally urged 50 toward the other, means actuated by said member holding the first mentioned contact device away from the other, said means being adapted to become inoperative when the speed of the film falls below a certain 55 rate.

9. In a motion picture projection machine, in combination, film advancing means, a member adapted to be rotated by engagement with the film, a pair of electrical contact devices normally tending to move toward closed position, a centrifugal governor adapted to hold said contact devices in open position, a second centrifugal governor 60 operated by the said member, and 65 means whereby said second governor controls operation of said first governor.

10. In a motion picture projection machine, in combination, film advancing means, a member adapted to be rotated by engagement 70 with the film, a pair of electrical contact devices normally tending to move toward closed position, a centrifugal governor adapted to hold said contact devices in open position, a second centrifugal governor 75 operated by the said member, and means whereby said second governor controls operation of said first governor, said means including a pair of clutch members connected to the respective governors and adapted 80 to be moved into engagement by the second governor.

In testimony whereof I have signed my name to this specification this 26th day of February, 1918.

ANTHONY CHIARELLI.
